CLAIM

The ornamental design for an electronic atomizing device as shown and described.

DESCRIPTION

FIG. 1 is a perspective view of an electronic atomizing device according to our design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of area 9 circumscribed in FIG. 1.

The broken lines consisting of evenly spaced dash lines in the drawings depict portions of the electronic atomizing device that form no part of the claimed design.

The broken lines consisting of short and long dash lines encircling the enlarged detail views are for annotative purposes that form no part of the claimed design.

The oblique shade lines in the drawings show transparency. All unshaded surfaces between solid and broken lines form no part thereof.
